UNITED STATES PATENT OFFICE.

ELMER A. SPERRY, OF BROOKLYN, NEW YORK.

UNIVERSALLY-MOUNTED SEARCHLIGHT.

Application filed April 19, 1918. Serial No. 229,436.

To all whom it may concern:

Be it known that I, ELMER A. SPERRY, a citizen of the United States of America, residing at 1505 Albermarle Road, Brooklyn, 5 in the county of Kings and State of New York, have invented certain new and useful Improvements in Universally-Mounted Searchlights, of which the following is a specification.

10 This invention relates to searchlights especially adapted for anti-aircraft and other military purposes. The necessities of modern warfare have developed a number of defects in searchlights such as at present used, 15 and the object of this invention is to overcome these defects.

In following an aircraft at night it is highly essential that the searchlight be moved quickly and easily so that the beam 20 may be kept steadily on the rapidly moving aeroplane. At the same time it is equally essential that the operator who directs the beam be located at a distance from the searchlight, since, as is now well known, an 25 object cannot be seen clearly from a point adjacent the searchlight owing to the reflection of dust or moisture in the air. To accomplish these purposes it has been proposed to locate the observer at a distance from the 30 searchlight and to operate the searchlight by signals sent from the observer to a searchlight operator, but such a system has been found too slow for aeroplane work. I am also aware that complicated electric, distance 35 controls, so called, have been proposed, but such controls are too costly and complicated for trench warfare, where the life of a searchlight averages probably not more than a week, and where the rough usage renders 40 complications highly objectionable.

Referring to the drawings which disclose the preferred form of the invention:

Fig. 1 is a plan view in more or less diagrammatic form of a searchlight placed 45 on the ground in the manner proposed in my invention.

Fig. 2 is a section through the ground showing the mounted searchlight and controls in separate holes in the ground.

50 Fig. 2^a is a detail in section showing the support for one end of a controlling rod.

Fig. 3 is a corresponding view of a modified form of the searchlight.

Fig. 4 is an end elevation of the searchlight 55 showing the supporting plates used in Fig. 3.

Fig. 5 is a corresponding view showing the

form of supporting plates preferably used in Figs. 1 and 2.

Fig. 6 shows a slightly modified form of angle plate or support which has been reinforced by a bracket.

Fig. 7 is an enlarged view of the gearing shown in Fig. 2.

Fig. 8 is another modified form of mechanism for operating a searchlight, and 65

Fig. 9 is a detached detail of this modification showing the bail and coacting parts.

The searchlight proper 1 is shown as pivotally supported upon a horizontal axis 2—2 within a gimbal ring 3. Said ring in 70 turn is pivotally supported on horizontal pivots 4—4 in supporting plates 5—6. Preferably the two axes of support of the searchlight are perpendicular.

The searchlight, it will be noted, instead 75 of normally assuming a horizontal position, or in other words, instead of normally projecting a horizontal beam is adapted to be pointed vertically upward; the direction of the beam in azimuth being controlled entirely by the oscillation of the light about either or both of the horizontal pivots instead of about a vertical axis as is usually the case. Each plate 5—6 is preferably constructed of angle iron with a sufficiently broad flat base 7 to rest upon any character 85 of earth or mud usually encountered in the battlefield. The bearings 8 and 9 for the pivots 4—4 are preferably of sufficient length to maintain the plates in proper alignment 90 and to prevent binding. Underneath the searchlight a hole 10 is preferably provided in which the operator may stand without exposing himself to shell-fire. The light may be surrounded by a circle of sand bags 95 11 or the like, if desired (see Fig. 3). The light is normally operated from distant holes 12—13 which may be connected with the central hole 10 and with each other by means of passage ways 14—15, so that the operator 100 may pass from one hole to the other without being observed or exposing himself. In each of the holes 12—13 is provided mechanism for controlling the searchlight beam. These holes may be spaced as much as ten or 105 twenty feet from the searchlight and one or more control rods 16 and 17 extend from said holes to the searchlight. Both rods are shown as journaled in an angle plate 18 supported adjacent the edge of hole 12 and 110 extend from this plate to the searchlight. Both rods are preferably provided with uni-

versal joints 19 and 20. A shaft 21 journaled in the bracket 6 is connected to rod 16 through said joint 19 and is also provided at its opposite end with a universal 5 connection 22 linking said shaft to a similar rod 16' extending in substantially the opposite direction. The rotary movement of said shaft is transmitted to the gimbal 3 by means of any suitable gearing such as a 10 chain 23 connected to sprocket pinion 24 on said shaft and to a larger sprocket wheel 25 on the shaft 4 supporting the gimbal. It will be readily apparent when either shaft 16 or 16' is turned that the searchlight will be 15 oscillated about pivots 4-4. Rod 17 is shown as connected to a second shaft 26 journaled in a bracket 27 through said universal joint 20. Bracket 27 is mounted upon or forms a part of the gimbal ring 3 so that 20 it partakes of the motions of said ring. Shaft 26 may be connected by means of similar universal joint 28, to a similar rod 17' extending in an opposite direction from rod 17 and in substantially the same direction as the rod 16'. The rotation of shaft 25 26 may be transmitted to the searchlight by means of bevel pinions 29 and 30 mounted respectively on said shaft and on a second shaft 31 journaled in said bracket 27. The 30 shaft 31 is shown as provided with a worm 32 which meshes with a worm wheel sector 33 secured to the trunnion arm 34 of the searchlight (Fig. 7). It will be readily apparent therefore that as either the rod 35 17 or 17' is rotated the searchlight will be oscillated about pivot 2-2 and also that the searchlight beam may be directed in any desired direction by oscillation about either or both axes of support. Each shaft is 40 shown as provided with a hand wheel 36, 37, 36' or 37' of a suitable form for turning the shaft. Shafts 16' and 17' are also shown as supported in an angle plate 18' similar to plate 18. The said shafts, especially shafts 45 46 17 and 17' are severally journaled in the plates 18 and 18' so that the changes in direction of the shaft occasioned by the movements of the searchlight about pivots 4-4 will not cause binding of the shaft in the 50 end plates. If desired, said shafts may be provided with universal joints 39 at or near the said angle plates as shown in Fig. 3, or a ball or swivelling bearing block 50 may be provided for the shaft in plate 18' (Fig. 55 2^u). In each case, it should be noted that the long shafts are connected to the searchlight through reduction gearing so that while a rapid turning of the beam may be effected, at the same time an accurate adjustment of the beam may also be accomplished.

The current is shown as led into the searchlight through a flexible cable 35 which will not interfere with the oscillation of the 60 light. In connection with this light I pref-

erably employ a ventilating system similar to that disclosed in my copending application on anti-aircraft searchlight, filed on even date herewith, Serial No. 229,485. According to this system the control box 70 which supports the electrode holders 71 is mounted out of alignment with the pivots.

It should be noted that the two pairs of rods 16 and 17 and 16' and 17' are so arranged that when the operator is facing the 75 light he may in each case rotate the right-hand hand-wheel 37 or 37' in the proper direction for sending the beam toward him or away from him; while he turns the left hand-wheel 36 or 36' in the proper direction for turning the beam clockwise or counter-clockwise, as it appears to him. It should also be noted that the arrangement is such that handles 36 or 36' are each rotated in the same direction that the beam is 80 turned, while rotation of handles 37 or 37' in the same direction relative to the operator will turn the beam toward or away from the operator in each instance. For these purposes the shafts 16 and 17 are 85 shown as crossed as they lead to the hole 12.

In the modification shown in Figs. 3 and 4 the shaft 116 is shown as passing under the searchlight, being journaled in the brackets 5' and 6' near their base. As 95 before the rods 116 and 116' are connected to a central shaft 40 through universal joints 41 and 42. Shaft 40 is geared to oscillate the gimbal ring 3 through a pinion 44 on said shaft and a gear sector 45 secured to the gimbal ring. Shafts 117 and 117' are each connected to a shaft 26' as before, through universal joints 20'. In this instance shaft 26' is provided with a worm 32' which meshes directly with a 105 worm segment 33' on the searchlight. The brackets 5' and 6' may or may not be provided with a reinforcing angle iron 50, if desired (see Fig. 6).

In Figs. 8 and 9 a third modification is 110 shown wherein a single rod is made use of to effect movements of the searchlight about both axes. According to this modification a long rod 51 is both slidably and rotatably mounted in the brackets 5', 6' and 118. The said rod is provided with an elongated pinion 52 which meshes with gear sector 45 to rock the searchlight about pivots 4-4, in other words, to rock the gimbal 3 115 on its pivot.

For moving the searchlight about pivots 2-2 I make use of a reciprocating or longitudinal movement of rod 51. For this purpose I may provide a swinging loop or bail 53 which is pivoted in ears 73 125 in a member 54 secured to the uprights 5' and 6'. Preferably the pivots 55 and 56 of loop 53 are in line with the axis 2-2 of the searchlight. The bottom of the searchlight is shown as provided with a 130

pin 57 carrying a roller 58 which engages in a trackway 59 in the loop. By this or similar means the searchlight is caused to follow all movements of the swinging loop 5 about the axis of the bail but may be freely moved about the axis 4—4 independently of the bail. For rocking the loop a link 60 is shown connecting the lower portion of the loop with a collar 61 rotatably but 10 non-slidably mounted on the rod 51. The rod 51 may be rotated by the handle 36 as before. The rod may be moved longitudinally either by pushing directly on the rod or by means of gearing. For this 15 purpose a handle 37 is shown mounted on a shaft 62 journaled on bracket 118. On said shaft is mounted a worm 63 which engages a rack bar 64 which is loosely mounted on shaft 51 but is non-slidably 20 secured thereon by means of fixed collars 65. By this means an accurate positioning of the searchlight may be secured. One of the bearings 119 of shaft 62 in block 118 may be open at the top so that worm 63 25 may be lifted out of engagement with rack 64 when not in use so as not to interfere with movement of shaft 51 from the other end.

The operation of my invention will be 30 apparent from the foregoing description.

The searchlight having been positioned as shown in the drawings, may be readily operated by one man who may also act as the observer. After starting the light the 35 observer may pass through passageway 14—15 to one or the other of holes 12 or 13. He may then, by operating handles 36 and 37 throw the beam in any desired direction. Thus, by turning the handle 40 36 clockwise or counter-clockwise he may throw the beam to the right or left as desired and by turning the handle 37 in one direction or the other he may throw the beam away from him or throw it toward 45 him at will. If the object assumes a position so that it is necessary to throw the beam toward the operator he may then quickly pass through passage 14 to the other hole 13 and operate the searchlight 50 from that end. It will be readily apparent therefore that no matter what position the object assumes the operator may always be in an advantageous location to observe it.

In the modification shown in Fig. 8 the 55 operation is of course similar as far as the movements of the operator are concerned; the rotation of the handle 36 moving the searchlight beam clockwise or counter-clockwise, while rotation of the handle 37 moves 60 the beam backwards and forwards.

In accordance with the provisions of the patent statutes, I have herein described the principle of operation of my invention, together with the apparatus, which I now con-

sider to represent the best embodiment 65 thereof, but I desire to have it understood that the apparatus shown is only illustrative and that the invention can be carried out by other means. Also, while it is designed to use the various features and elements in the 70 combination and relations described, some of these may be altered and others omitted without interfering with the more general results outlined, and the invention extends to such use. 75

Having described my invention, what I claim and desire to secure by Letters Patent is:

1. The combination with a searchlight mounted for oscillation about a horizontal 80 axis, of a rod extending outwardly from and secured to the same for oscillating it about said axis and a second rod extending in substantially the opposite direction for a similar purpose, whereby the operator may 85 keep on a side away from the beam.

2. The combination with a support, of a gimbal ring mounted thereon, a searchlight journaled for oscillation with said ring, a shaft also journaled on said ring, a universal 90 connection from said shaft to a distant control handle, and gearing connecting said shaft and searchlight to oscillate the same within the ring on rotation of the shaft.

3. In a military searchlight system, the 95 combination with a searchlight, a universal support therefor, distant control means for oscillating the lamp about a plurality of axes, said means being located on opposite sides of said searchlight, whereby the operator may select a position depending upon the direction in which the beam is pointing. 100

4. In combination, a member mounted to turn about a horizontal axis, a searchlight mounted within said member for turning 105 about a horizontal axis in substantially the same plane as the first mentioned axis, and at an angle thereto, and a plurality of sets of means for oscillating said searchlight about either of said axes, said sets being 110 positioned on different sides of the searchlight so that the operator may select an operating position depending upon the direction in which the light beam is projected.

5. In combination, a support, a gimbal 115 ring pivotally mounted thereon, a searchlight mounted for pivotal movement within said ring, means including a plurality of rods extending in opposite directions for turning said ring from either of a plurality 120 of distant points, and means including a plurality of oppositely projecting rods extending substantially in the same direction as the first mentioned rods for turning said searchlight within said ring. 125

In testimony whereof I have affixed my signature.

ELMER A. SPERRY.
